UNITED STATES PATENT OFFICE.

JAMES HENDERSON, OF CAMBUSBARROW, NEAR STIRLING, NORTH BRITAIN.

LABEL-HOLDER.

SPECIFICATION forming part of Letters Patent No. 228,757, dated June 15, 1880.

Application filed June 28, 1879. Patented in England November 17, 1877.

To all whom it may concern:

Be it known that I, JAMES HENDERSON, of the town of Cambusbarrow, near Stirling, North Britain, engineer, have invented an Improved Label or Card Fixer for Railway Cars or Trucks, of which the following is a specification.

The invention relates to a device for securely holding cards, labels, way-bills, or printed directions to the sides of railway cars or trucks.

The object of my invention is to provide a device which will securely hold any card, way-bill, or printed or written directions in firm attachment to the sides of cars or trucks, so as to be in plain view; and when desirable to be removed or replaced the card or other paper may be readily detached by simply pulling on a loop or ring, and another card be put into place, when the device, on being released, will spring back and bind it to the side of the car until intentionally removed.

The invention consists in an elastic binder, made in the form hereinafter more particularly described, and a grooved bar, so arranged in relation to each other that the grooved bar will support the lower end of the card or other paper, while the elastic binder will clamp the same at its upper portion and securely bind it to the side of the car or truck.

In the accompanying drawings, in which similar letters of reference indicate like parts, Figure 1 represents a front elevation of my invention, illustrating one modification of the improved elastic binder. Fig. 2 is a longitudinal sectional view taken through the binder at about the middle of its width. Fig. 3 is a vertical sectional view. Fig. 4 is an edge view of the binder when detached, and illustrating a modification of the form of pulling loop or ring. Fig. 5 is a face view of the same, and Fig. 6 represents a face view and edge view of the clips or ties for securing the binder to the sides of the car.

In the drawings, A represents a side of the car or truck to which the device is to be applied.

B is a wooden or metallic bar provided with a rabbet or groove, a. This bar is placed preferably vertically, though it may be placed hori-

zontally, if desired, and with the groove a 50 next the side of the car or truck, and is secured in place by screws or other equivalent devices.

C is an elastic binder, made of metal, either steel or spring-brass, and preferably of flat 55 material, though round or half-round material may be employed. The outer ends of this binder are turned back, as shown in Fig. 4, so as to hold against the clips or ties D when secured in place.

At about the middle of the length of the binder is provided a ring, b, as shown in Figs. 1 and 2, or a loop, b', (shown in Figs. 4 and 5,) which ring or loop is intended as a means by which the operator may draw the body of the 65 binder forward when a paper is to be placed in position or removed. This binder, when detached, has the form shown in edge view, Fig. 4. With this form the binder will be made stiff when its ends are held down to the 70 wood by the clips D D, as in Fig. 1.

The binder C is secured by clips D D to the side of the car at several inches from the grooved bar B. This distance will be governed by the size of the card to be held, as indicated by card E. (Shown by dotted lines in Fig. 1.)

When it is desired to place a card and fix the same, the operator will with his fingers pull on ring b, or equivalent loop b', and draw 80 the middle portion of the binder out from the side of the car and insert card E behind the binder, carrying the end of the card into groove a of the bar B, as indicated in Fig. 1. When he permits the binder to spring back against 85 the card it will be held there. To remove the card the operator will pull forward the binder, when it may be readily taken from its place.

It will be readily seen that this device is simple, and when once properly placed will not 90 be liable to be injured by accident or get out of order, and will at all times be ready for use. Its use will obviate all necessity of using tacks or nails, and way-bills or printed directions or invoices attached to cars to accompany freight 95 can be removed without being torn or marred and filed away for future reference.

This invention is substantially the same in-

vention for which Letters Patent of Great Britain No. 4,302 were granted to me on the 17th day of November, 1877.

Having described my invention, what I desire to secure by Letters Patent is—

1. The combination and arrangement of the elastic binder C, made in the form described and shown; and provided with pulling-ring b, or equivalent loop b', with the clips D, all adapted to be placed and secured to the side of a car or truck, substantially as described, for the purpose set forth.
2. The combination, with the elastic binder, as described, and binding-pieces D D, of the grooved bar B, arranged in relation to the said

binder for operation substantially as and for the purpose set forth.

In witness whereof I, the said JAMES HENDERSON, have hereunto set my hand this 24th day of May, in the year of our Lord 1879.

JAS. HENDERSON.
